(57) **CLAIM**

The ornamental design for an endform for hose, as shown and described.

DESCRIPTION

FIG. 1 is a perspective view of an endform for hose showing our new design;

FIG. 2 is a reverse perspective view thereof;

FIG. 3 is a cross-sectional view thereof;

FIG. 4 is a first side view thereof;

FIG. 5 is a second side view thereof;

FIG. 6 is a third side view thereof; and,

FIG. 7 is a lateral cross-section view thereof taken along line 7—7 in FIGS. 4 and 5.

The BrassCraft name plate forming part of the claimed design is a registered trademark of BrassCraft.
